GAS PRODUCER AND OTHER FURNACE

Albert Leet Galusha, Caldwell, N. J.

Application July 17, 1930. Serial No. 468,634

8 Claims. (Cl. 126—182)

This invention deals with the construction of the wall for a combustion chamber and with an ash brake mounted on the wall. The invention was made with particular reference to problems 5 arising in gas producer construction but may be used in furnaces of other sorts or wherever conditions demand or warrant it. One purpose is to eliminate the need of a brick lining on the interior of the combustion chamber wall and to 10 make possible a water-jacketed metal wall that will not cause the fire bed to be cooled to the extent of preventing complete combustion near the wall but nevertheless will itself be kept below a temperature that would cause it to melt. 15 It is the aim also to provide an ash brake that can be mounted on a water-jacketed wall. In the ash brake there is embodied a feature of construction illustrated in the stirrer arms described here as well as in my co-pending application 20 Serial No. 294,132, filed July 20, 1928, and applicable to any cantilever arm extending into a fuel bed in suchwise as to be subjected to a bending stress upon rotation of the grate.

In the drawings—

25 Fig. 1 is a view in central vertical section through a gas producer in the region of the grate, showing the grate with stirrer arms, the water-jacketed wall and the ash brakes:

Fig. 2 is a top plan view of the part of a producer shown in Fig. 1:

Fig. 3 is a detail view, in section through the water-jacketed wall, showing the construction of the latter and of the ash brake mounted thereon, drawn to a larger scale:

35 Fig. 4 is a view in section on the line 4—4 of Fig. 3:

Fig. 5 is a view in vertical section of an alternative form of wall construction.

In the drawings the invention is shown applied to a gas producer of the type shown in my co-pending application Serial No. 468,635, filed July 17, 1930. In the type of gas producer there are shown two spaced annular shells 10, 11, (Fig. 2), form the wall, providing a water chamber between them. Ordinarily such shells are designed for strength only and the inner shell 10 is from $\frac{3}{8}$ inch to $\frac{3}{4}$ inch thick. According to the prevailing practice before this, the interior of the inner shell would be lined with fire brick either 40 in the region of combustion only or for the full height of the combustion chamber. But fire bricks lead to the formation of clinkers which become cemented on the wall, thus decreasing the size of the region of combustion and disturbing the uniformity of burning. If, however, the brick lining is omitted, the fire is cooled and combustion is retarded near the wall,—obviously an undesirable condition since more of the 45 fuel burns to dioxide gas instead of monoxide

gas which it is desired to make in a gas producer.

As a solution of this problem, I add to the heat resistance of the inner shell in order that the heat transfer through the shell to the water, though sufficient to prevent overheating of the shell, may be retarded enough to keep the fire bed from being undesirably cooled. I may do this in several ways, such as by putting a coating of heat resistant material on the outer side of the inner shell or by adding a supplemental shell close to the inner one, or by making the inner shell several times thicker than is necessary for strength alone, or by adding a number of ribs on the outer side of the inner shell. The result 50 in each case is to increase the resistance, or to decrease the rate of heat transfer, two or three times or more, and that maintains the temperature of the inner side below the fusion point of the metal but above a point at which combustion would be retarded near the wall.

When the effect is gained by using a thicker wall, the thickness is of the order of about one inch and upward, being from $\frac{1}{8}$ inch to $1\frac{1}{2}$ inches or more. The added thickness may be in a 55 supplemental shell 12 (Figure 3) or it may be in an integral over-size shell 10' (Figure 1). The horizontal annular ribs 13 (Figure 5) will give the same result.

The grate is of the construction described in 60 my co-pending application Serial No. 294,132 filed July 20, 1928, which is characterized by its vertically spaced annular plates 26 of progressively smaller size. Each plate overlaps the inner edge of the one beneath it and the conical 65 cap 27 overlaps the top plate. The outer margin of the lowermost plate is preferably concentric with the grate axis, which is in the center of the circle defined by the wall of the combustion chamber, and underlies the heavy bosh ring 28 100 at the lower rim of the said wall. The inner rim of this lower plate is eccentric of the grate axis, as are the inner rims of the other plates, and as the outer rim of each plate above the lowest is substantially concentric with the inner edge 105 of the plate beneath it, the outer edges of these other plates are eccentric of the grate axis. The inner rims of the plates above the lowermost one may or may not be eccentric of their respective peripheries, but in any event the eccentricities of 110 both inner and outer rims of all the plates are in a single radial direction. Any suitable driving mechanism may be used to turn the grate as for example the one shown in my copending application Serial No. 294,132 previously referred to. 115 Preferably it has the capability of variation in the rate of rotation.

This grate provides a full horizontal supporting area for the fuel but, by reason of the vertical clearance between plates, ash can be received 120

between them for discharge over their inner margins. Due to the eccentricity of the inner margins, the rotation of the grate causes these margins to move laterally as well as rotarily. The 5 movement of the edges of the grate plates away from the wall of the furnace lets the ash drop onto the plates below. The movement of the plates of the grate towards the wall causes those plates to saw into the ash and break up the clinkers, and to push some of the ash forcibly between 10 the grate plates and to discharge that ash over the inner margins of those annular plates and into the ash pit.

A similar downward movement occurs by reason of the eccentricity of the outer margins which, in effect, advance toward and recede from any given point on the wall; and as the ash and clinkers drop they come into a smaller space between the grate and the wall until finally a 15 level is reached at which they are subject to a slicing action by one plate or another, with the wall acting as an abutment. The result is that the body of ash is cut into pieces small enough to be discharged.

20 The action of the grate depends upon relative movement between the plates and the fuel bed but on the other hand a slow rotation of the fuel bed, for instance of the order of one rotation in a day, is desirable as it distributes the effect of non-uniform draft, different rates of burning and other non-uniform factors affecting different regions in the fuel bed to a different extent.

In order to prevent or retard the rotation of the bed of fuel with the grate I mount on the 25 wall of the producer a number of ash brakes which extend into the fuel bed, preferably into the ash layer, that being the part upon which the drag is directly exerted.

In the mounting of the stirrer arms and the 30 ash brake arms I employ constructions which make possible the continued use of the same members despite the bending of them which occurs due to their being cantilever members. The bending force on the stirrer arms is the drag of 35 the ash through which they move and is principally exerted along the line of travel of the arms. The force on the ash brake members is due to the pressure of the ash in the direction of grate rotation as the ash is urged around by 40 the grate and by the stirrer arms. The susceptibility to bending is increased in the case of both by the heating effect which sometimes is very great, as when the burning of the fuel 45 proceeds in such a way as to include the arms in the region of actual combustion.

As described in my pending application Serial 50 No. 294,132 of which this application forms a continuation in part in respect of the expedient just described, the stirrer arms 30 have base flanges 31 held to the grate plates by bolts 32, one on each side of the arm in the path in which the arm travels. By removal of these bolts, the arms 30 can have their positions reversed.

The ash brake arms 35 are preferably circular 55 in cross section and each is held to a base plate 36 by a nut 37 on a threaded extension 38 of the arm passing through the plate. Each plate 36 is secured to the outer face of a hollow boss 39 in the outer wall of the producer by studs 40 and 60 41. When an arm 35 becomes bent, all that is necessary is to loosen the nut 37, and then turn the arm 180 degrees, and tighten up the nut 37 again. Thus the arms 35 can be adjusted from

the outside of the producer without stopping its operation and without permitting escape of gas.

Referring again to the construction of the water jacket wall, I may explain that in making producer gas and in pre-heating the moist air going to the furnace, but a fraction of a pound of steam or its equivalent is needed for each pound of solid fuel gasified.

If a gas producer with a complete water jacket were used with the ordinary metal water jacket, 85 the flow of heat to the water would be far in excess of the steam consumption requirements. In order to keep the saturated air temperature correct and the steam production accordingly it would be necessary to employ a large amount of jacket cooling water far in excess of the steam consumption requirements.

90 My special wall construction above described greatly reduces the total heat flow per hour to the water in the jacket and by this construction I am enabled to increase the efficiency of the machine and to reduce the production of steam and to reduce the use of water to approximately the amount required for use in the fire to make gas.

I claim:

1. In a furnace, a stepped rotary grate in combination with arms on the different levels of said grate extending into the fuel bed and subjected to bending stresses upon rotation of the grate, and securing means on opposite sides of said arms in the direction of said bending stresses whereby said arms may be reversed to apply the bending stresses in a relatively opposite direction to said arms.

110 2. A furnace having a rotary grate in combination with means projecting into the fuel space from the inner wall of the furnace to retard the bed of fuel rotating with the rotation of the grate.

115 3. A furnace having a rotary grate provided with stirrer arms in combination with means projecting into the fuel space from the inner wall of the furnace to retard the bed of fuel rotating with the rotation of the grate.

120 4. A furnace having an eccentrically mounted rotary grate consisting of superposed spaced plates in coned formation in combination with means projecting into the fuel space from the inner wall of the furnace to retard the bed of fuel rotating with the rotation of the grate.

125 5. A furnace having an eccentrically mounted rotary grate consisting of superposed spaced plates in coned formation and carrying stirrer arms in combination with means projecting into the fuel space from the inner wall of the furnace to retard the bed of fuel rotating with the rotation of the grate.

130 6. A furnace having a rotary grate provided with reversible stirrer arms in combination with means projecting into the fuel space from the inner wall of the furnace to retard the bed of fuel 135 rotating with the rotation of the grate.

7. A furnace having a rotary grate in combination with reversible arms carried by the wall of the furnace and projecting into the fuel space to retard the bed of fuel rotating with the rotation 140 of the grate.

145 8. A furnace having a rotary grate in combination with arms projecting through the side walls of the furnace, and means accessible from the outside for adjusting the arms, said arms projecting into the fuel space to retard the bed of fuel rotating with the rotation of the grate.

ALBERT LEET GALUSHA.
